UNITED STATES PATENT OFFICE.

JOHN HILDEBRAND, OF BRIDGEPORT, CONNECTICUT.

AUTOMATIC BOILER.

1,230,296.

Specification of Letters Patent. Patented June 19, 1917.

Application filed January 22, 1917. Serial No. 143,633.

To all whom it may concern:

Be it known that I, JOHN HILDEBRAND, a subject of the Emperor of Austria, residing at Bridgeport, in the county of Fairfield and 5 State of Connecticut, have invented certain new and useful Improvements in Automatic Boilers, of which the following is a specification.

This invention relates to certain new and 10 useful improvements in automatic boilers.

The primary object of the invention is the provision of a device whereby the gas supply of a burner is automatically shut off upon the boiling of the contents of a receptacle positioned thereon.

A further object of the device is the provision of an attachment for gas burners operating with a boiler carried means whereby such means is automatically shifted upon 20 the violent boiling of the fluid within the boiler and whereby such attachment turns the inlet valve of the burner up to its closed position.

In the drawing forming a part of this 25 application and in which like designating characters refer to corresponding parts throughout the several views:—

Figure 1 is a sectional view through a boiler and a portion of a stove provided with 30 the present device, the burner being illustrated by dotted lines.

Fig. 2 is a top plan view thereof, parts being broken away.

Fig. 3 is a sectional view taken upon line 35 III—III of Fig. 1.

Fig. 4 is a sectional view taken upon line IV—IV of Fig. 2, looking toward the top of the sheet.

Fig. 5 is a perspective view of a bracket 40 carried by the main gas supply pipe.

Fig. 6 is a view of the float operating means carried by the boiler, the same being detached and partially broken away.

Fig. 7 is a perspective view of the detent 45 member for the trip valve.

Fig. 8 is a perspective view of the trip member, and,

Fig. 9 is a perspective view of the releas- 50 ing weight member employed with the device.

The invention being especially serviceable in connection with gas stoves, the same is herein illustrated formed as an attachment for the stove 10 having a burner 11 illustrated therein by dotted lines, the said stove being provided with the usual gas supply

pipe 12 having a valve 13 for feeding gas to the said burner, a swinging handle 14 being provided for the said valve.

The bracket 15 is provided with a clamp 60 16 for positioning the same upon the pipe 12, a fork 17 being carried by the said bracket for the accommodation of the inlet nipple 18 of the valve 13. An angular trip 19 is pivoted to the bracket 15 by a bolt 20, a 65 spring 21 being carried by the said trip and bracket for normally holding the trip in a plane parallel with the pipe 12 at a point above the valve 13 with the depending finger 22 of the said trip in contact with the valve 70 handle 14 resiliently maintaining the same in its closed position.

A releasable detent member 23 is pivoted as at 24 to the bracket 15 having a depending beveled foot 25 adapted to receive the 75 ear 26 of the trip 19 therebehind for maintaining the trip in its set position with the spring 21 under tension and with the finger 22 at a distance from the valve handle 14 as best illustrated in Fig. 3 of the drawings. 80 A spring 27 connects the bracket 15 with the detent member 23 tending to normally maintain the foot 25 thereof within the path of movement of the ear 26 of the said trip.

The stove attachment already described 85 operates to maintain the trip in its set position engaged by the detent member 23, it being understood that when the upper cross-piece 28 of the said detent member is moved away from the stove, the foot 25 thereof will 90 be released allowing the spring 21 to swing the trip 19 with the finger 22 passing through an arcuate path and engaging the handle 14 for swinging the same to its closed position as illustrated by dotted lines in 95 Fig. 3 of the drawings.

A coöperating attachment is provided for a boiler 29 adapted for operatively shifting the releasable detent member 23 while said boiler is operatively positioned over the 100 opening 30 of the stove 10 beneath which opening the burner 11 is positioned. A hollow float 31 is arranged upon the fluid 32 within the boiler 29, a post 33 being mounted upon the float. A catch member 34 is pivotally mounted to a lug 35 carried by the handle 36 of the boiler 29, said catch member having a hook 37 extending through a slot 38 in the said handle while the lever portion 39 of the catch member is adjustably 105 pivoted to the post 33 by means of a pin 40 carried by the free end of the said lever

adapted for pivotal reception within the desired one of a plurality of openings 41 in the said post. A retaining latch 42 is pivoted to the lever 39 having an off-set end 43 adapted to engage the opposite side of the post 33 from the lever 39 when the latch is closed for removably retaining the catch member in engagement with the float member.

10 An operating weight or releasing member 44 is pivoted to the free end of the handle 36, as at 45, the free end of said releasing member being enlarged in the form of a block 46 and having a path of movement intersecting the plane of the cross member 28 of the releasable detent member 23.

With the boiler 29 arranged over the burner 11 upon the stove 10, the gas being turned on and lighted, the handle 14 will 20 extend outwardly as herein illustrated and the releasing weight member 44 will be adjusted beneath the handle 36 having a projecting lip 47 carried by the block 46 engaged by the hook 37, the float 31 being 25 freely positioned upon the fluid 32. When a sufficiently high point has been attained by the liquid when boiling in the container, the float 31 will have been elevated to the desired point to cause the operation of the releasing device by the adjustable connection 30 between the post 33 and the arm 39.

The elevating of the fluid 32 shifts the catch member 34, releasing the hook 37 from the releasing member 44 whereby the weight 35 46 swings downwardly striking the detent member 23 for allowing the trip 19 to force the valve handle 14 to close the valve 13, thereby shutting off the supply of gas from the burner 11. A serviceable attachment is 40 provided which will not interfere with the ordinary use of the gas stove but which may be employed with a boiler or cooker provided with the coöperating attachment controlled by the boiling of the fluid contained 45 therein.

What I claim as new is:—

1. A turn-off means for gas stoves com-

prising in combination with a gas valve handle thereof, a bracket arranged adjacent the said handle, a spring impelled trip carried by the said bracket having a path of travel in the closing path of travel of the said handle, a releasable detent member adapted for retaining the said trip in its set position, a boiler, and automatic means 55 for releasing said detent member carried by the said boiler and partially positioned therein.

2. A turn-off means for gas stoves comprising in combination with a gas valve handle thereof, a bracket arranged adjacent the said handle, a spring impelled trip carried by the said bracket having a path of travel in the closing path of travel of the said handle, a releasable detent member adapted 60 for retaining the said trip in its set position, a boiler, a handle upon the said boiler, a releasing member pivoted to the said handle having a path of movement intersecting the plane of the said detent member, a supporting catch member for the said releasing member, a float within the said boiler, and adjustable connections between the said float and catch member.

3. A float operated shut-off for gas stoves 75 comprising in combination with a stove having a burner with a gas supply pipe and valve connections, an operating handle for the said valve, a bracket removably clamped to the said pipe, a spring-operated trip pivoted to the said bracket provided with a depending finger adapted to move said handle to close the valve, a detent member for said trip provided with an angular beveled foot, such trip being provided with an ear adapted for seating back of the said foot when the trip is set, a return spring for the said detent member, a boiler positioned over said burner, and automatic means for releasing said detent member carried by said boiler and operable upon a pre-determined amount 80 of boiling of the contents of said boiler.

In testimony whereof I affix my signature.

JOHN HILDEBRAND.
